UNITED STATES PATENT OFFICE

NORRIS F. MCNAUGHT AND EDWARD H. PETERSON, OF CHICAGO, ILLINOIS, ASSIGNEES
TO DURO METAL PRODUCTS COMPANY, OF CHICAGO, ILLINOIS, A CORPORATION OF
ILLINOIS

VALVE GRINDER

Application filed November 9, 1931. Serial No. 573,816.

Our invention is concerned with the provision of improvements in those valve grinders which are operated by rolling their handles between the hands of the operator.

5 The present invention provides means for receiving the necessary downward thrust of the hands upon the tool and for preventing the hands of the operator from descending on the handle during the normal operation 10 of the tool, these objects being accomplished without hampering that free movement of the hands which is necessary if the tool is to be most effectively and satisfactorily manipulated.

15 In the accompanying drawing illustrating a preferred embodiment of our invention,

Fig. 1 is an elevational view of our improved valve grinder as it appears when in operation; and

20 Fig. 2 is a similar view showing certain parts of the tool in axial section.

Similar characters of reference refer to similar parts throughout the drawing.

In the drawing reference numeral 1 indicates an engine block provided with a poppet valve 2, the light unseating spring which usually is placed under the heads of engine valves during the grinding thereof being illustrated at 3. At 4 we have shown upwardly projecting stud bolts which often are found on engine blocks in the vicinity of their valve seats.

25 The valve grinder comprises a wooden handle 5, the upper portion of which is cylindrical or substantially so, the handle being provided with a lower end 6 of reduced cross section which is adapted to be received and tightly embraced by the stem portion 7 of a rubber vacuum cup 8.

30 As thus far described, the valve grinder is not substantially different from valve grinders with which the art has been familiar for some time. We shall now describe those features of our improved tool which greatly increase its effectiveness and make it safer to use.

35 Mounted on the handle 5, something more than a hand's breadth from the top thereon, is a metal collar 9 held firmly in position by 40 brads 10, said collar 9 having an annular

shoulder 11. Disposed around the collar 9 for free rotation thereon is a sleeve 12, the upper end of this sleeve being shouldered against and riveted over a concavo-convex metal annulus 14, the convex surface of the annulus 14 being upwardly presented.

45 In the use of the valve grinder, the vacuum cup 8 is applied to the top of the valve 2 and the upper cylindrical portion of the handle 5 is pressed between the palms of the hands of the mechanic so that the handle may be oscillated first in one direction and then in the other by simultaneous movements of the hands in opposite directions.

50 In the tool of the present invention the annulus 14 constitutes a rest for the lower edges of the hands and receives the requisite downward thrust upon the tool without, however, hampering the to and fro movements of the hands of the mechanic. Since the lower edges of the hands engage the annulus at points more distant from the handle axis than are the points at which the palms of the hand press against the handle, it is important that the handle and the annulus be relatively rotatable, i. e. so that they may oscillate at different speeds when the tool is in use.

55 It will be understood that the annulus 14 will prevent the hands of the mechanic from sliding down on the handle of the tool and thus will prevent their injury due to accidental contact with the stud bolts 4 or other protuberances which frequently are found on engine blocks in the vicinity of valves to be ground.

60 Having thus illustrated and described a preferred embodiment of our invention, what we claim is new and desire to secure by Letters Patent of the United States is:

65 1. In a valve grinder of the type operated by rolling its handles between the palms of the hands of the operator, a handle, means for operatively connecting the lower end of the handle with a valve, an annulus mounted on the handle a hand's breadth or more below the upper end thereof and constituting a support for the lower edges of the hands of the operator, said annulus being held against downward movement on the handle and being capable of free rotation on the handle, so that

the handle and annulus may oscillate at different speeds under the influence of the palms and the lower edges respectively of the hands of the operator.

5. 2. In a valve grinder of the class described, a handle provided at its lower end with means for facilitating its attachment to a valve, an annulus rotatably mounted on the handle a hand's breadth or more from the upper end thereof, and means carried by the handle affording a thrust bearing for said annulus.

10. 3. In a valve grinder of the class described, a rotatable handle, means at the lower end of the handle adapted to facilitate its application to a valve to be ground, an annulus mounted on the handle and located a hand's breadth or more below the upper end thereof, said annulus having a convex upper surface and being freely rotatable upon the handle but held against downward movement thereon.

15. 4. In a valve grinder of the class described, a handle, a vacuum cup at the lower end thereof adapted to be applied to the upper surface of a valve to be ground, and an annulus mounted on the handle between its ends, said annulus adapted to rotate at one speed under the influence of the lower edges of the hands of the operator as and when the handle is rotated at a different speed under the influence of the palms of the hands of the operator.

20. 5. A valve grinder of the class described having a handle the lower end of which is adapted for operative engagement with a valve to be ground, and a concavo-convex annulus horizontally and rotatably disposed on said handle a hand's breadth or more below the upper end thereof, the convex surface of said annulus being upwardly presented, said annulus being adapted to rotate at one speed under the influence of the lower edges of the hands of the operator as and when the handle is rotated at a different speed under the influence of the palms of the hands of the operator.

In witness whereof, we hereunto subscribe our names this 5th day of November, 1931.

50. NORRIS F. McNAUGHT.
EDWARD H. PETERSON.
